UNITED STATES PATENT OFFICE

115,072

DESIGN FOR A COMBINED WATCH AND COMPASS

William R. Shillaber, New York, N. Y.

Application August 24, 1938, Serial No. 79,553

Term of patent 7 years

To all whom it may concern:

Be it known, that I, William R. Shillaber, a citizen of the United States, residing at New York, in the county of New York and State of New York, have invented a certain new, original, and ornamental Design for A Combined Watch and Compass, of which the following is a specification, reference being had to the accompanying drawing, forming a part thereof.

Figure 1 is a top plan view of a combined watch and compass showing my new design;

Figure 2, an end elevation;
Figure 3, a side elevation; and
Figure 4, a perspective view with cover in raised position.

I claim:

The ornamental design for a combined watch and compass, as shown.

WILLIAM R. SHILLABER.
